Macdonald & Macdonald,
ATTORNEYS.

UNITED STATES PATENT OFFICE.

HERMANN FREDERICK SCHELLING, OF GRANTWOOD, NEW JERSEY.

NEEDLE HOLDER FOR TALKING MACHINES.

Application filed May 10, 1920. Serial No. 380,018.

To all whom it may concern:

Be it known that I, HERMANN FREDERICK SCHELLING, a citizen of the United States, residing at Grantwood, in the county of Bergen and State of New Jersey, have invented certain new and useful Improvements in Needle Holders for Talking Machines, of which the following is a full, clear, and exact specification, such as will enable others skilled in the art to which it appertains to make and use the same.

My invention relates to sound reproducing apparatus and more particularly to improvements in the stylus or needle holding device which is necessary on all forms of so-called talking machines.

One object of my invention is to provide a needle holding arrangement which is simple to manufacture, of low cost and compact and neat in appearance.

A further object is to provide such a needle holding arrangement so constructed as to normally hold the needle firmly in place and yet permit of its ejection when desired principally by the force of gravity and of the insertion of a new needle with a minimum amount of effort.

These objects and such others as will be apparent as the description proceeds, are attained by the combination and arrangement of parts described in the specification and particularly pointed out in the claims, one practical embodiment of my invention being shown in the accompanying drawing in which Fig. 1 is a view of the stylus lever and needle holding device, partly in section showing the manner in which it is operated. Fig. 2 represents an end view of the needle holding device. Fig. 3 represents a section on the line A—A of Fig. 1.

Similar numerals refer to similar parts throughout the several views.

It is a matter of common knowledge that the needles of talking machines must be frequently changed depending upon the quality and nature of the needle itself and the frequency and duration of use of the machine. It is desirable, therefore, that such needle changing may be rapidly and conveniently done and with a minimum of effort on the part of the operator. At the same time, it is absolutely essential to the proper and best operation of the machine that the needle when in place may be gripped firmly so as not to rock, tilt or slide while in use.

Referring now to the drawing in which I

have illustrated one mode of applying my invention for the purposes recited, the diaphragm 4 has attached to it by wax 3 or other desired means, the stylus arm 1 pivoted as at 2 in the usual way. At the needle end of the arm is a compartment in which the sliding pin 13 is located having an operating head 8 and passing through the guide opening 15. A flattened portion 14 of the pin enables the set screw 9 to limit the inward motion of the pin by abutting the face 17 and to limit the outward motion by abutting the edge 18. The pin 13 is essentially cylindrical, with the flattened portion 70 spoken of and a portion cut away forming V-shaped grip 16 which co-operates with a flat side of the triangular opening 7 through which the needle 6 passes. A spring 12 is held within the casing 10 by the pin or screw 75 11 the head of which serves a purpose to be described presently.

The spring 12 acts against the pin 13 holding the same towards its outward position and firmly gripping the needle 6 as in 80 a vise, the V-shaped jaw of the pin holding the needle 6 against the flat face 19 of the opening 7.

To remove the needle it is not necessary to turn the sound box upward as heretofore; the head of the pin 11 and the head 8 of the button 13 are grasped between the thumb and forefinger and pressure is applied, compressing the spring 12 and positively releasing the needle 6 so that it may 90 fall out free of the flat face 19 by the action of its own weight.

If in any conceivable manner the needle should stick in the V-notch of the button 13, the end 20 of the opening 7 will knock off 95 and free the needle as the button is pressed farther in to the right as shown. A new needle may be inserted easily by pressing the button 13 fully in and when the needle is inserted in the opening 7 the button is released, automatically straightening the needle in three directions by the faces of the clamping jaws and holding the needle firmly by the action of the spring.

Having thus described my invention and one method of utilizing the same, what I desire to claim is:—

1. In a needle holding device, a compartment containing a spring, a pin co-operating with said spring and having a button, and a flattened portion, a set screw abutting said flattened portion and limiting the motion

thereof, a flat jaw on one side of said compartment, a V-shaped jaw on said pin and finger gripping means co-operating with the button on said pin, whereby said jaws may be separated.

2. In a needle holding device, a compartment containing a spring, means for holding said spring and having finger gripping means, a pin co-operating with said spring

and having a flattened portion, a set screw 10 abutting said flattened portion and limiting the motion thereof, a flat jaw on one side of said compartment, a V-shaped jaw on said pin and finger gripping means comprising a button co-operating with said first 16 named finger gripping means, whereby said jaws may be separated.

HERMANN FREDERICK SCHELLING.
